UNITED STATES PATENT OFFICE.

WILL R. JOHNSON, OF MONTFORT, WISCONSIN.

PUMP-ROD LIFTER.

No. 821,645.

Specification of Letters Patent.

Patented May 29, 1906.

Application filed February 19, 1906. Serial No. 301,882.

To all whom it may concern:

Be it known that I, WILL R. JOHNSON, a citizen of the United States, residing at Montfort, in the county of Grant and State of Wisconsin, have invented a new and useful Pump-Rod Lifter, of which the following is a specification.

This invention relates to devices for lifting pump rods or tubes from wells and for similar purposes, and has for its object to improve the construction and increase the efficiency of devices of this character.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

25 In the drawings, Figure 1 is a side elevation, and Fig. 2 is a plan view, of the improved device applied. Fig. 3 is a perspective view of the lower grip detached. Fig. 4 is a perspective view of the base-plate detached.

30 The improved device comprises a base member 10, preferably of a hard-wood plank having a recess 11 in one side and with a U-shaped metal shield 12, encompassing the recess and secured in place by bolts 13. Attached to the base member 10 is a plate 14, having spaced ears 15, between which a link 16 is pivoted at 17. Pivoted at 18 in the upper end of the link 16 is a bar 19, enlarged at 40 the free end into a U-shaped portion 20, the latter having "nip-plates" 21 22 for bearing by the knife-edges against the opposite sides of the rod or tube (represented at 23.) The portion 20 of the clamp member is provided with an arm 24 for assisting in releasing the clamp when required. Attached to the base 45 10 is a socket 25, in which a standard 26 is rotatively mounted. Pivoted at 27 in the standard 26 is a lever 29, having a handle 30 at one end and a link 31, pivoted at 32, at the other end. Pivoted at 33 at the lower end of the link 31 is an arm 34, having a grip-band 35 at the outer end for encircling the tube or rod 23. The grip-band 35 is provided with

knife-edges 36 37 for bearing against opposite sides of the tube or rod 23, as shown. By this simple arrangement a tube or rod may be grasped by the band 35 and elevated by bearing down upon the lever 29, and when the limit of the stroke of the lever is reached the clamp member 19 20 will automatically engage the rod and hold it suspended, while the lever is elevated to cause the grip-band to be engaged at a lower point, the rod or tube being thus elevated step by step, as will be obvious.

When the tube or rod 23 is being suspended by the lower or clamp member, it bears at one point against the binding member 12 and the latter thus serving in a two-fold capacity as a support for the base-plank 10 and as a means coacting with the clamp member for holding the rod while the lifting mechanism is being adjusted to a new position.

Having thus described the invention, what I claim is—

1. In a device of the class described, a base member having a lateral recess, a U-shape plate forming a binding to said recess, a standard swinging from said base contiguous to 80 said recess, an arm swinging from the free end of said standard and having a U-shaped terminal for receiving the rod to be elevated, nip-plates at opposite sides of said U-shaped terminal for bearing against opposite sides of 85 said rod, and means for elevating said rod.

2. In a device of the class described, a base member having a lateral recess, a U-shape plate forming a binding to said recess, a standard swinging from said base contiguous to 90 said recess, an arm swinging from the free end of said standard and having a U-shaped terminal for receiving the rod to be elevated, nip-plates at opposite sides of said U-shaped terminals for bearing against opposite sides 95 of said rod, a socket upon said base member, a standard rotatively disposed in said socket a lever swinging from said rotative standard, a grip-band through which said rod passes, and coupling means between said band and 100 lever.

In testimony that I claim the foregoing as my own I have hereto affixed my signature in the presence of two witnesses.

WILL R. JOHNSON.
